BOWSTRING AND METHOD OF
MAKING SAME

Nathaniel B. Lay, Pine Bluff, Ark.

Application August 29, 1947, Serial No. 771,187

8 Claims. (CL. 28—74)

1

My invention relates to improvements in methods of making archery bowstrings of the multiple strand type exemplified in my U. S. Letters Patent No. 2, 271,173 dated January 17, 1942.

The primary object of my invention is to provide for forming multiple strand bowstrings with end loops in less time than can be accomplished by present practices, and with the strands arranged to be uniformly tensioned, relatively, throughout the strings, under reaction of the bow, and the end loops sheathed so as to prevent the same from fraying, and reinforced to better withstand wear than in the bowstrings of commerce.

To the accomplishment of the above, and subordinate objects presently appearing, a preferred practice of my improved method has been illustrated in the drawings accompanying and forming part of this specification, set forth in detail in the succeeding description, and defined in the claims appended hereto.

In said drawing:

Figure 1 is a view in perspective illustrating the manner in which the strands for forming the bowstring are pulled out to even the ends thereof;

Figure 2 is a similar view illustrating the manner in which the ends of the strands are folded preparatory to applying the sheath;

Figure 3 is a view in perspective illustrating the manner in which the sheath is applied;

Figure 4 is a similar view further illustrating the manner in which the sheath is applied;

Figure 5 is a view in perspective illustrating the manner in which the loop is pre-formed;

Figure 6 is a view in perspective illustrating the manner in which the loop is finished;

Figure 7 is a detail view in transverse section taken on the line 7—7 of Figure 4;

Figure 8 is a view in perspective illustrating the manner in which my method may be practiced in applying a sheath to the middle portion of the bowstring.

Reference being had to the drawings by numerals, and first to Figures 1 to 7 thereof, according to the practice of my method as illustrated therein, in forming the bowstring the ends of a suitable number of strands 1, of linen, cotton, or other suitable material, and sufficient in number to provide for the requisite strength in the bowstring are grasped by one hand and pulled out straight so that said ends are substantially even and as illustrated in Figure 1.

A loop is formed at one, or each end, of the strands 1, as may be required, and as follows.

2

The ends of the strands 1, while grasped by the one hand, are folded over a flexible wire 2 held in the other hand and which is bent upon itself into a loop 3, all as shown in Figure 2. Thus the ends of the strands 1 are folded over the wire 2 preparatory to applying the sheath for the loop.

The wire 2 is next inserted through a suitable length of tubular sheathing 4, such as tubular shoe or corset lace, or the like, as shown in Figure 3, and with the folded ends of the strands 1 held at the adjacent portion of said strands to prevent said ends from slipping and becoming unfolded.

15 The wire 2 is next pulled through and out of the length of sheathing 4, as shown in Figure 4, so as to pull the folded ends of the strands through and out of said sheathing and then unfold said ends and free the same. A sheath is thus formed around an end portion of the strands 1 of sufficient length to cover the end loop, when completed.

The sheathed end portion of the strands 1, designated 5 in Figure 5 is then folded at its 25 approximate center around a fixed peg 6, as shown in Figure 5, to pre-form the loop and the freed ends of the strands 1 are then sized to the adjacent portion of the strands as represented by dotted lines in Figure 5, and by means of glue, 30 latex, or any other suitable means, not shown.

The sized ends and the adjacent portion of the strands 1 to which the same are sized, together with the ends of the sheathing 4, are now wrapped, as at 8, to bind the same together, by suitable 35 means such as cord and as shown in Figure 6.

Thus, a loop 7 is completed on the end of the string with a sheathing 4 covering the same to prevent chafing of the strands and reinforcing said loop.

40 The entire string, except the loop 7, or loops, may be twisted, or the strands left loose, as desired.

The described method may be practiced in part in applying a sheathing 9 to the central 45 portion of the bowstring as shown in Figure 8. The sheathing 9 may be applied in substantially the same manner as described with reference to the sheathing 4 and slid along the strands 10 into proper position to be secured thereto by 50 binding the ends of the same to said strands 10, as represented at 11.

The foregoing will, it is believed suffice to impart a clear understanding of my invention, without further explanation.

55 Manifestly, the invention, as described, is susceptible of modification without departing from

the inventive concept, and right is herein reserved to such modifications as fall within the scope of the appended claims.

What I claim is:

1. The herein described method of forming archery bowstrings comprising arranging a plurality of strands side by side with the ends even at one end of said strands, folding said ends to form a loop, pulling said loop through a tubular sheathing so as to apply the sheathing over said strands and then pulling the loop unfolded so as to free said ends, and securing the ends of the sheathing to said strands.

2. The herein described method of forming an archery bowstring comprising arranging a plurality of strands side by side with the ends even at one end of said strands, folding said ends to form a loop, pulling said loop through a tubular sheathing so as to apply said sheathing to a portion of said strands and then pulling said loop unfolded to free said ends, folding the sheathed portion of said strands to form a loop, and securing the free ends to an intermediate portion of said strands to close the loop.

3. The herein described method of forming an archery bowstring comprising arranging a plurality of strands side by side with the ends even at one end of said strands, folding said end to form a loop, pulling said loop through a tubular sheathing so as to apply the sheathing to a portion of said strands and then pulling said loop unfolded to free said ends, folding the sheathed portion of the strands to form a loop, sizing said free ends to an intermediate portion of the strands and wrapping said sized ends and intermediate portion.

4. The herein described method of forming an archery bowstring comprising arranging a plurality of strands side by side with the ends even at one end of said strands, pulling said ends through a tubular sheathing to free said ends and apply the sheathing to a portion of the strands with said ends projecting out of said sheathing, folding the sheathed portion of the strands to form a loop, and securing the projecting ends to an intermediate portion of said strands.

5. The method of forming a bowstring which comprises arranging a plurality of threads in side by side relation longitudinally to form a main body portion, telescoping preformed textile sleeves over the ends of the thread, bending the sleeve-covered sections on themselves to form loops, and securing the bent over ends to the main body portion.

6. The method of forming a bowstring which comprises arranging a plurality of threads in side by side relation longitudinally to form a main body portion, telescoping preformed woven textile sleeves over the ends of the thread, bending the sleeve covered sections on themselves to form loops, and securing the bent over ends to the main body portion.

7. A bowstring having end loops of preformed textile sleeves telescoped over the ends of the main body portion.

8. A bowstring having end loops of preformed textile tubular sleeves telescoped over the ends of the main body portion, and servings of thread to bind the loop ends to said body portion.

NATHANIEL B. LAY.
